UNITED STATES PATENT OFFICE.

JOHN E. BELL, OF BROOKLYN, NEW YORK, ASSIGNOR TO SINCLAIR REFINING COMPANY, OF CHICAGO, ILLINOIS, A CORPORATION OF MAINE.

OIL DISTILLATION.

Application filed October 7, 1921. Serial No. 506,082.

To all whom it may concern:

Be it known that I, JOHN E. BELL, a citizen of the United States, residing at Brooklyn, county of Queens, State of New York, have invented certain new and useful Improvements in Oil Distillation, of which the following is a specification.

My invention relates more particularly to the distillation of crude petroleum and has for its object in one operation to effect the division of the numerous hydrocarbons of different specified gravities and boiling points contained in the oil into the desired number of cuts. In the process of fractional distillation as ordinarily practiced the oil is slowly heated through the range of temperatures in which the desired distillates are given off, the vapors being condensed as they are given off. Cuts are made at successively higher temperatures, the particular points at which the cuts are made being determined by the gravities of the components which are to be embraced in the respective fractions or cuts, as they are more commonly called.

It is the object, for obvious reasons, to make the division between the cuts as sharp as possible, that is to say, to avoid the presence in any cut of hydrocarbons other than those of the desired gravities. In practice, however, this has been only approximately attained, some compounds of heavier gravities being carried over with those of lighter gravities and some of the lighter oils remaining after the temperature has been raised above their boiling points.

It is the purpose of my invention to improve the results of the distillation operation in respect to the sharpness of the cuts and economy and efficiency of operation. With this in view I provide a number of stills, which preferably is at least equal to the number of cuts to be made, flowing the oil through the stills seriatim, and maintain the stills in the series at temperatures which rise successively from the first still, which receives the crude petroleum to the last still from which the residue is drawn off. The oil is preferably flowed continuously from the first to the last still, receiving additional heat in each successive still by which components of successively higher boiling points are vaporized and driven off. The vapors from each still (except the first) are caused in a still of lower temperature, thereby being largely condensed. Preferably the vapors from the higher temperature still pass into a coil in the lower temperature still in which the temperature of the vapors is lowered and the bulk thereof condensed, and the uncondensed portions thereof are permitted to escape into the vapor space of the still of lower temperature, mingle with the vapors formed therein, and pass to the condenser in the next still of yet lower temperature. It is known that, other things being equal, the nearer the temperature of the condensing surface or medium is to the temperature of the vapor being condensed, the heavier the condensate and the better the separation or cut effected between the hydrocarbons condensed and the hydrocarbons which escape as vapors. By leading the vapors from a still of the series into the still of next lower temperature and condensing them therein, this condition, favorable to accurate cutting, is realized. Furthermore, the heat necessary for conducting the distillation is economized in this manner as the vapors condensing in the condensing coils in the several stills give up their heat of vaporization as well as the heat to which the temperature difference is due to the oil therein.

In the preferred form of invention I also employ an additional condensing means between successive stills in which means the heavier vapors are to some extent condensed, preferably by being sprayed with reflux condensate from the condenser coils in one or more of the stills of lower temperature. The condensate may be taken off separately from the respective still condensers and intermediate condensers but ordinarily, and in the specific embodiment of my invention shown and hereinafter described, I prefer to take off the condensate at the intermediate condensers only. In the preferred embodiment of the invention I further economize heat by passing the oil between stills through heat exchangers through which condensate from condensers of higher temperature flows, thus not only raising the temperature of the oil before it enters the still of higher temperature but lowering the temperature of the condensate. Other objects and advantages of my invention will be gathered from the drawings and the following description in which I have set forth the preferred form of my invention; it is to be

understood, however, that the specific disclosures are for the purpose of exemplification only and that the scope of the invention is defined in the following claims in which I have endeavored to distinguish it from the prior art so far as known to me, without, however, relinquishing or abandoning any portion or feature thereof.

In the accompanying drawing Figs. 1 and 10 1^a, taken together, show a distillation plant embodying my invention in a preferred form, in front elevation; Figs. 2 and 2^a together constitute a plan view of the same, parts being broken away to show the 15 prior construction; Fig. 3 is a vertical section of an element thereof; Fig. 4 is a vertical longitudinal section of one of the stills of the plant, parts being shown in elevation; Figs. 5 and 5^a show a section on the line 2 5—5 of Figs. 2 and 2^a, Fig. 6 shows a vertical section of a detail, and Figs. 7 and 8 diagrammatically show pairs of adjacent stills with associated apparatus and schematically illustrate the operation of the apparatus. In the specific form of the invention chosen for illustration the plant 25 comprises ten stills, though the number thereof in practice will depend upon the number of cuts which it is desired to make.

30 The oil to be treated after being pre-heated in an apparatus to be presently described, is fed to the first still 10^a, which is maintained at the lowest temperature of the series and thence is fed successively to stills 35 10^b, 10^c, 10^d and others, its temperature being raised step by step until it reaches the final still 10^k of the series from which the tarry residue is removed in liquid form. Fractional distillation is accomplished in 40 this manner, the distillates or cuts from the successive stills being successively of higher average boiling points.

Before entering the first still 10^a of the series the oil to be treated is first pre-heated 45 by means of the hot tarry residue from the last still of the series in a group of heat exchangers 11^a, 11^b, 11^c, seen at the right of Fig. 1^a, which are similar in construction, and one of which is shown in section on an 50 enlarged scale in Fig. 3. Looking first at the last named figure it will be seen that each of these heat exchangers comprises a cylindrical shell 12 with ends 13, 14 which are closed except for the inlet opening 15 in the bottom end and the outlet opening 16 in the upper end. The interior of the interchanger is divided into a lower oil chamber 17, an upper oil chamber 18 and an intermediate hot tar chamber 19 by horizontal 55 heads 20, 21. The heads are connected by tubes 22 through which the oil introduced through the bottom opening passes through the hot tar chamber into the upper oil chamber. From the latter the oil escapes through the outlet opening 23. The tubes 22, to

which reference has been made, extend upwardly beyond the head 20 and are perforated near their upper ends so as to spray the oil into the upper chamber. A small amount of vapor is formed in each of these 70 upper chambers by the heating and spraying and escapes through the vapor opening 16. The bottom opening of the first heat interchanger is connected to some suitable source of oil to be treated and the 75 outlet opening 23 of said heat interchanger, is connected by pipe 24 to the inlet opening of the next heat interchanger in order, and the oil outlet opening of this second heat interchanger 11^b is connected by pipe 25 to 80 the oil inlet opening of the third heat interchanger 11^c. The oil outlet opening of the last said heat interchanger is connected by pipe 26 to the inlet of the first still 10^a. The vapor outlets 16 of the respective heat 85 interchangers are connected by pipes 27 to the vapor line 28 from the first of the stills.

The hot tar chamber in each of the heat interchangers is provided with an upper inlet opening 29 and a lower outlet opening 30 90 and with baffles 31. The hot tar entering at the top of the tar chamber flows downwardly about the oil tubes therein and in a direction the opposite of that of the oil, and imparts its heat to the latter. The tar inlet 95 opening of the last of the elements 11^c is connected by pipe 32 to the last and hottest of the stills, and receives its supply of hot tar therefrom. From heat interchanger 11^c the hot tar flows through pipe 33 to the tar 100 chamber of the second heat interchanger, and from the latter by pipe 34 to the tar chamber of the first heat interchanger 11^a from which it may be led away to any suitable storage receptacle in relatively cool 105 condition.

The stills may all be of identical construction, except in so far as modification may be necessary because of the end positions of the first and last stills, respectively. 110 In the preferred form of the invention shown in the drawings, however, I have provided means for introducing steam into the four hottest stills shown at the left of Fig. 2 and this makes it desirable to introduce certain differences in construction which will be hereafter specifically described. All of the stills are alike, however, in that each comprises a horizontal drum 35 of usual form, having the usual vapor dome 36. 115 Each still may also be heated in any well-known or preferred manner and it has therefore not been thought advisable to complicate the drawings by showing the heating 120 means.

125 It will be convenient to first follow the flow of oil through the series of stills and then to describe the course of the vapors. Reference has already been made to the fact that the oil is introduced at the rear end 130

of the first still by the pipe 26 leading from the last of the heat interchangers. The oil is drawn off from the first still 10^a at the front end thereof and on the side opposite 5 from the inlet at 37. From the outlet 37 it is led downwardly by pipe 38 to a manifold 39 by which it is distributed through a number of heat interchangers 40^a through which condensate from the stills of higher 10 temperature is led, as will be later described, thus heating the oil. From the heat interchangers 40^a the oil is collected by a manifold 41 and conveyed by pipes 42/43 to the rear end of still 10^b. The connections between stills 10^a, 10^b, 10^c, * * * 10ⁱ are similar to those described between stills 10^a and 10^b, so that between the stills of each pair except the last two the oil is raised in temperature by heat absorbed from the condensates from the stills of higher temperature. From the still 10ⁱ oil is led to the last still 10^k directly by the pipe 43. As each of the stills is maintained at a somewhat higher temperature than the immediately preceding still the temperature of the oil is raised step by step, and the components thereof, except the heaviest, are driven off in vapor form in groups of successively higher boiling points, known in the art as cuts.

I shall now describe the disposition that is made of the distillates driven off from the respective stills beginning with that of the highest temperature shown at the left end of the series in Figs. 1 and 2; but first it is to be observed, as previously mentioned, that the four stills of highest temperature are supplied with steam through a main 44, branches 45 leading the steam from said main to stills 10^g, 10^h, 10ⁱ, 10^k, which are provided each with a series of longitudinally extending pipes 46, connected to the respective branches and perforated or slotted to direct the steam into the heavy oil at the bottom of the still. By the introduction of the steam the oil is agitated and circulated in the respective stills and the formation of carbon and coke reduced, and, what is of more importance, the temperatures of vaporization are lowered.

The vapor domes of the respective stills are connected by pipes 47 to a vapor line 48 at the front of the series of stills. The branch lines 47 are provided with valves 49 which are normally open and the vapor line 48, is provided with a pair of valves 50, 51 between each pair of branches 47, one or the other of said valves being normally closed to prevent the direct flow of vapors through said line. A downcomer pipe 52 receives the vapors from each of the stills and conducts them to a condenser 53, the uncondensed vapors from the latter escaping by pipe 54 to a condenser 55 in the still of next lower temperature.

The condensers 53 are alike throughout the plant and the description of one will serve for all. The construction is shown in vertical section in Fig. 6. It comprises a shallow rectangular casing 56 divided by a horizontal header 57 in which is mounted a large number of tubes 58 which extend upwardly from the header and are closed at their upper ends by the top wall 59 of the casing. Each of these tubes opens into the condensate space 60 below said header and is perforated at 61 near the top thereof. Above the header is the vapor space or chamber 62 into which such tubes project and this chamber communicates with the downcomer vapor line 52 through a vapor inlet 63 formed in the end member 64 of said cascade condenser. A vapor outlet 65 is formed in end member 66 of the cascade condenser and communicates with pipe 54, above mentioned, which leads the vapors from the cascade condenser to the still condenser 55 in the still of next lower temperature. The end member 66 is also formed with a reflux inlet chamber 67, which receives reflux condensate from an inlet pipe 68, a port 69 permitting the condensate to flow into the chamber 60 of the cascade condenser. The end member 64 is formed with a condensate outlet chamber 70 which communicates at 71 with the vapor chamber near the bottom thereof and also with condensate outlet tubes 72 and 73.

The operation of the cascade condenser will appear from the above description. The vapors entering the inlet 63 flow through the vapor chamber in a circuitous course about the tubes therein and the reflux condensate entering the chamber 60 is sprayed through the pipes 58 into the vapors in the vapor chamber, partially cooling the vapors and condensing the heavier components thereof and being heated to some extent thereby. The condensate collects in the bottom of the vapor chamber and flows therefrom to the condensate outlet chamber 70 and thence through the outlet pipes 72 and 73. The reflux from the last cascade condenser of the series, to wit, that shown at the left in Fig. 1, is led by pipes 73 and 74 to the heat interchanger 40^a of a series of heat interchangers to which reference has heretofore been made, serving to heat the oil in its passage from still to still. From heat interchanger 40^a the oil passes by pipe 75^a to heat interchanger 40^b, and so on through each of the heat interchangers of the series and is finally drawn off in relatively cool condition through pipe 76.

As heretofore stated, the vapors which are not condensed in the cascade condenser just described flow through the pipe 54 to a still condenser 55 in the still of next highest temperature. The construction of this still condenser 55 is shown in dotted lines in

Figs. 2 and 5. In the former figure stills 10^s, 10^t, 10^k are broken away to show this construction but that in still 10^h is identical therewith. The still condensers each 5 comprise a longitudinal pipe 77 located near the bottom of the still into which pipe 54 leads. A large number of branch pipes 78 are connected to the main pipe 77 and are so distributed thereon as to extend to every 10 part of the still, the body of the pipes being substantially submerged in the oil, but the ends thereof, which are open, extend into the vapor space in the still. The vapors entering this still condenser from the still 15 of higher temperature are largely condensed therein, the branch pipes forming a condenser of large superficial area maintained at the temperature of the oil in this still which is somewhat lower than the temperature 20 of the vapors as they enter the condenser. By reason of the relatively small temperature differential between the vapors and the condenser and the extensive working surface of the latter, the vapors are condensed under most favorable conditions for 25 making a sharp cut as previously stated. A small proportion of the vapors are uncondensed and escape through the ends of the condenser tubes into the vapor space of the 30 still in which the condenser is located and mingle with the vapors generated in the still which are of nearly similar character.

Thus in the case of each of the stills into 35 which steam is introduced, which for the sake of brevity I shall call the steam stills, the vapors after undergoing a preliminary cooling and partial condensation in a cascade condenser, are condensed in a condenser in the still of next lower temperature and 40 the uncondensed vapors from such condenser incorporated with the vapors generated in such still and passed along the series.

The cuts or fractional products are preferably taken off at the respective cascade condensers, the ninth cut, to wit, that of highest 45 average gravity, being taken off from the last cascade condenser 53^s, the eighth cut, which is next in order of gravity, being taken off from the next cascade condenser 50 53^t, and so on. The condensate discharged into each cascade condenser is mainly drawn from the still condenser into which the vapors from such cascade condenser are led, thus the condensate discharged into the last 55 condenser 53^t by pipes 79, 68, and the condensate from the still condenser in each of the other stills, (except the last, which contains no condenser) is discharged into the cascade condenser, from which it receives 60 vapors through similar pipes 79 and 68. The supply of condensate may be more or less supplemented by condensate received from the adjacent cascade condenser of lower temperature through pipe 80.

65 As best seen in Figs. 2 and 2^a, for each

cascade condenser there is a series of heat interchangers similar to that described in connection with the last condenser, through which the cuts or condensates are separately carried, giving up its heat to the oil flowing 70 in a reverse direction through such series of heat interchangers. The specific construction of these heat interchangers is immaterial, provided they afford contiguous passages for the oil and condensate, respectively, whereby the absorption of heat by the one from the other is facilitated.

Were steam introduced into all of the stills of the series, or were no steam introduced into any of them, the construction 80 heretofore described, including the still condensers, might be carried throughout the series to advantage. But while there is a material advantage in introducing steam into the hotter stills to effect the agitation 85 of the heavy oil therein, diminish coke deposition and by its partial pressure reduce the boiling point, it is undesirable in the stills of lower temperature and in which the oil is of lighter average composition because by its partial pressure it disturbs the end points of the cuts. It is for this reason that steam is only introduced into the stills of highest temperature and as the 90 vapors therefrom contain steam it is undesirable to introduce them into the vapor spaces of the non-steam stills. In the non-steam stills, therefore, I provide separate condensers for the vapors coming from the steam stills and from the non-steam stills of 95 higher temperatures, respectively, the condensers for the vapors containing steam being closed while the condensers for the vapors which do not contain steam open into the vapor spaces of the respective stills. 100 In Fig. 2 I have shown in plan and in Fig. 4, in vertical section, a still containing the separate condensers. In Fig. 2 the still 10^t is shown as so provided, it being understood that all the stills shown to the right thereof 105 are similarly equipped. The larger condensers occupying the front portions of the still are of the open variety, similar in all respects except length, to the open still condensers previously described. The closed 110 condensers, located at the rear ends of the respective stills comprise upper and lower headers 86, 87 connected by small bent vapor tubes 88, see Fig. 5^a. The vapor introduced into the lower header from the 115 still of higher temperature rises in the multiple small tubes and is largely condensed therein, the uncondensed vapors flowing into the upper header and thence out of the still and through header 95 and pipe 97 to the 120 still of next lower temperature. While I have shown the last of the non-steam stills 10^t as containing an open condenser this is not used where steam is used in the steam stills, for the reason above stated, but only 125 130

when no steam is used. When steam is on in the steam stills the vapor from still 10^a instead of being led through vapor line 52 to condenser 53 and pipe 54 to the open condenser 55, is carried by pipes 89, 90, 91 to the lower header 87 in said still. For this purpose the valve 92 in pipe 52 is closed and valves 93, 94, in the vapor manifold 48 and downcomer pipe 89 respectively, are open. The non-steam stills are provided at their rear ends with a vapor header 95 connecting the upper manifolds of the closed still condensers and provided between the stills of the respective pairs, with valves 96 to prevent direct flow therethrough. Downcomer pipes 97 provided with valves 98 lead the uncondensed vapors from the top manifold of each closed condenser to the bottom manifold of the following closed condenser so that the vapors coming from the steam stills are subjected to successively lower temperatures in the closed condensers of the non-steam stills and cuts made therefrom at the same respective temperatures as the cuts made in such stills in the open condensers therein. Because of the existence of the partial pressure of the steam in the closed condensers however, the fractions condensing in any particular closed condenser are heavier and of higher vaporizing temperature than the fraction condensing in the open condenser which has no such partial pressure. For obvious reasons it is desirable to combine condensates of as nearly similar character as possible and therefore the condensate from each closed condenser, instead of being combined with the condensate from the open condenser in the same still is added to the reflux from the open condenser of a hotter still, i. e., a still to the left thereof as shown in Figs. 1 and 1^a. In the particular arrangement illustrated the condensate from each closed condenser is added to the condensate from the open condenser of the adjoining hotter still. For this purpose a pipe 99 is connected to the lower header of each closed condenser and extends to the front of the battery or series of stills and then to the left, with reference to Figs. 1 and 1^a, being connected into the reflux pipe 79 of the next hotter still.

In Figs. 7 and 8 reference characters have been omitted and legends have been applied to show in a diagrammatic way the operation of the stills and associated apparatus in the distillation plant. Fig. 7 schematically shows the operation of adjacent stills where in both of them, or in neither of them, direct steam is used, such as stills 10^b and 10^c. Fig. 8 schematically shows the operation of adjacent stills where vapors containing steam are employed to heat the oil in the stills and are thereby condensed but where the uncondensed steam-containing

vapors are not allowed to mingle with the still vapors, such as stills 10^c and 10^d.

It is to be noted that the vapors pass through the cascade boxes or condensers successively from left to right, from hotter to cooler and the condensate or reflux from right to left, i. e., from cooler to hotter. The vapors are therefore submitted to fractional condensation by being sprayed with liquid which is sufficiently cooler than the vapors to effect the desired condensation of the lighter components of the vapors but whose temperature is sufficiently high to secure sharpness of cut. Likewise the condensate is subjected to fractional distillation in contact with successively hotter bodies of vapor which take up the lighter ends. By the combined fractional condensation and distillation thus effected the cuts or condensates from the respective reflux or cascade boxes are cleared up, the apparatus thus acting as a series of re-run stills.

The cuts or condensates from the respective reflux boxes or condensers are or may be maintained separate throughout the apparatus and may be separately stored or mixed in any desired proportions to form commercial products. In ordinary practice condensate is taken off only from those cascade boxes or condensers in which the condensate corresponds in flash point, etc., to commercial products for which there is demand. The products of the process all leave the system at relatively low temperatures after giving up their excess heat to the oil undergoing further treatment under conditions making for maximum heat economy, but little heat being lost beyond the inevitable losses due to radiation, etc. It will be noted moreover, that throughout the system the flow of cooling fluids is contrary to the flow of the heating fluids to which they impart heat so that great efficiency in heat absorption is realized.

I claim:

1. A process of fractional distillation and condensation of oil which comprises flowing the oil to be treated through a series of stills maintained at successively higher vaporizing temperatures, condensing part of the vapors given off in each still by absorbing heat therefrom by the oil in a still of lower temperature and heating the oil intermediate successive stills by the condensed vapors from stills later in the series.

2. A process of fractional distillation and condensation of oil which comprises flowing the oil to be treated through a series of stills maintained at successively higher vaporizing temperatures, condensing part of the vapors given off in each still by absorbing heat therefrom by the oil in the next still of lower temperature, and heating the oil intermediate successive stills by the condensed vapors from stills later in the series.

3. A process of fractional distillation and condensation of oil which comprises flowing the oil to be treated through a series of stills maintained at successively higher vaporizing temperatures, condensing part of the vapors given off in each still by absorbing heat therefrom, first by the condensate of these vapors formed in a still of lower temperature, and then by the oil in the said

5 still of lower temperature, and heating the oil intermediate successive stills by the condensed vapors from stills later in the series.

4. A process of fractional distillation and condensation of oil which comprises flowing the oil to be treated through a series of stills maintained at successively higher vaporizing temperatures, condensing part of the vapors given off in each still and absorbing heat therefrom, first by the condensate of

15 these vapors formed in a still of lower temperature mingled with condensate of vapors from the latter still and then by the oil in said still of lower temperature, and heating the oil intermediate successive stills by the

20 condensed vapors from the stills later in the series.

5. A process of fractional distillation and condensation of oil which comprises flowing the oil to be treated through a series of stills maintained at successively higher vaporizing temperatures, condensing part of the vapors given off in each still by absorbing heat therefrom by the oil in a still of lower temperature and isolating the condensate so formed, from the oil in the still of lower temperature, and heating the oil intermediate successive stills by the condensed vapors from stills later in the series.

6. A process of fractional distillation and condensation of oil which comprises flowing the oil to be treated through a series of stills maintained at successively higher vaporizing temperatures, condensing part of the vapors given off in each still by absorbing heat therefrom, first by the condensate of these vapors formed, in a still of lower temperature, and then by the oil in said still of lower temperature, isolating the condensate so formed, from the oil in the still of lower temperature, and heating the oil intermediate successive stills by the condensed vapors from the stills later in the series.

7. A process of fractional distillation and condensation of oil which comprises flowing the oil to be treated through a series of stills heated to successively higher vaporizing temperatures and condensing part of the vapors given off in each still by absorbing heat therefrom, first by condensate of these vapors formed in a still of lower temperature and then by the liquid oil in said still of lower temperature.

8. A process of fractional distillation and condensation of oil which comprises flowing the oil to be treated through a series of stills

heated to successively higher vaporizing temperatures, condensing part of the vapors given off in each still by absorbing heat therefrom, first by the condensate of these vapors formed in a still of lower temperature, and then by the liquid oil in said still of lower temperature, and isolating the condensate so formed.

9. A process of fractional distillation and condensation of oil which comprises flowing the oil to be treated through a series of stills maintained at successively higher vaporizing temperatures and condensing part of the vapors given off in each still by absorbing heat therefrom, first by the condensate of these vapors formed in a still of lower temperature, mingled with the condensate of the vapors given off in said still of lower temperature and then by the liquid oil in said still of lower temperature.

10. A process of fractional distillation and condensation of oil which comprises flowing the oil to be treated through a series of stills heated to successively higher vaporizing temperatures, condensing part of the vapors given off in each still by absorbing heat therefrom by the oil in a still of lower temperature, isolating the condensate so formed, from the oil in the still last mentioned and permitting the uncondensed vapors to escape with the vapors from the oil of that still, and heating the oil intermediate successive stills by the condensed vapors from stills later in the series.

11. A process of fractional distillation and condensation of oil which comprises flowing the oil to be treated through a series of stills heated to successively higher vaporizing temperatures, fractionally condensing the vapors from each still, except the first, by absorbing heat therefrom by the oil in the stills of successively lower temperatures, and heating the oil intermediate successive stills by the condensed vapors from stills later in the series.

12. A process of fractional distillation and condensation of oil which comprises flowing the oil to be treated through a series of stills heated to successively higher vaporizing temperatures, and fractionally condensing the vapors from each still, except the first, by absorbing heat therefrom, first by the condensate formed by condensation of these vapors in each of the stills of successively lower temperature and then by the oil in the said stills of successively lower temperatures, and heating the oil intermediate successive stills by the condensed vapors from stills later in the series.

13. A process of fractional distillation and condensation of oil which comprises flowing the oil to be treated through a series of stills heated to successively higher vaporizing temperatures, fractionally condensing the vapors from each still, except the first,

5 by absorbing heat therefrom by the oil in stills of successively lower temperatures, permitting the uncondensed vapors to mingle with the vapors given off in these stills, and 5 beating the oil intermediate successive stills by the condensed vapors from stills later in the series.

10 14. A process of fractional distillation and condensation of oil which comprises flowing the oil to be treated through a series of stills heated to successively higher vaporizing temperatures and fractionally condensing the vapors from each still, except the first, by absorbing heat therefrom, first 15 by the condensate of these vapors formed in each of the stills of successively lower temperature mingled with the condensate of vapors from the still in which such first mentioned condensate is formed, and then by 20 the oil in the said stills of successively lower temperature, and heating the oil intermediate successive stills by the condensed vapors from the stills later in the series.

25 15. A process of fractional distillation and condensation of oil which comprises flowing the oil to be treated through a series of stills, heated to successively higher vaporizing temperatures, condensing part of the vapors from each still, except the first, by 30 absorbing heat therefrom by condensates of vapors from stills of lower temperatures, and heating the oil intermediate successive stills by the condensed vapors from stills later in the series.

35 16. A process of fractional distillation and condensation of oil which comprises flowing the oil to be treated through a series of stills heated to successively higher vaporizing temperatures, condensing part of the vapors from each still, except the first, by 40 absorbing heat therefrom by direct contact with condensates of vapors from stills of lower temperatures, and heating the oil intermediate successive stills by the condensed vapors from stills later in the series.

45 17. A process of fractional distillation and condensation of oil which comprises flowing the oil to be treated through a series of stills heated to successively higher vaporizing temperatures and condensing part of the vapors from each still, except the first, by 50 spraying them with condensates of vapors from stills of lower temperature, mingled with condensates of the vapors first mentioned produced in said stills of lower temperatures.

55 18. A process of fractional distillation and condensation of oil which comprises flowing the oil to be treated through a series of stills heated to successively higher vaporizing temperatures and condensing part of the vapors from each still, except the first, by 60 spraying them with condensates of vapors from stills of lower temperatures, and condensing the vapors left uncondensed by

such treatment by absorbing heat therefrom by the oil in the stills of lower temperatures.

19. A process of fractional distillation and condensation of oil which comprises flowing the oil to be treated through a series of stills heated to successively higher vaporizing temperatures, condensing part of the vapors from each still, except the first, by spraying them with condensates of vapors from stills of lower temperatures mingled 70 with condensates of the vapors from the stills of higher temperatures produced by absorbing heat therefrom by the oil in stills of lower temperatures, then mingling the vapors uncondensed in such treatment with 75 the vapors given off in such stills of lower temperatures, and heating the oil intermediate successive stills by the condensed vapors from stills later in the series.

20. A process of fractional distillation and condensation of oil which comprises flowing the oil to be treated through a series of stills heated to successively higher vaporizing temperatures, condensing part of the vapors given off in each still by absorbing heat therefrom, first by the condensate of such vapors produced by such heat absorption and then by the liquid oil in a still of lower temperature, and heating the oil in its passage from still to still by causing it to absorb heat from the condensates of vapors from all the stills of higher temperature.

21. A process of fractional distillation and condensation of oil which comprises flowing the oil to be treated through a series of stills heated to successively higher vaporizing temperatures, condensing part of the vapors given off in each still by absorbing heat therefrom by the oil in a still 100 of lower temperature, preheating the oil prior to its entry into the first still by residuum from the last still and heating the oil between adjacent stills by imparting heat thereto by the condensates of vapors 105 given off in stills later in the series.

22. A process of fractional distillation and condensation of oil which comprises flowing the oil to be treated through a series of stills heated to successively higher vaporizing temperatures, condensing part of the vapors given off in each still by absorbing heat therefrom, first by the condensate of these vapors formed by such heat absorption and then by the liquid oil in a still of lower 110 temperature and preheating the oil prior to its entry into the first still by the residuum from the last still.

23. A process of fractional distillation and condensation of oil which comprises flowing the oil to be treated through a series of stills heated to successively higher vaporizing temperatures, condensing part of the vapors given off in each still by absorbing heat therefrom by the oil in a still 125

of lower temperature, heating the oil between adjacent stills by imparting heat thereto from condensates from all of the stills of higher temperatures, and preheating the oil prior to its entry into the first still by the residuum from the last still.

24. A process of fractional distillation and condensation of oil which comprises flowing the oil to be treated through a series of stills heated to successively higher vaporizing temperatures, introducing steam into the oil in a plurality of stills at the end of the series, condensing part of the vapors given off in each still by absorbing heat therefrom by the oil in a still lower temperature while isolating the vapors from the steam stills from the vapors of the stills into which steam is not introduced and mixing the condensate of the vapors given off in each steam still with the condensate formed in the still of next higher temperature.

25. In apparatus of the class described, a series of stills, means for maintaining the stills at successively higher vaporizing temperatures, means for feeding crude oil into the first still of the series and for conveying oil from each still to the next succeeding still of the series, means for introducing steam into the last still of the series, closed condensers in the preceding stills and connections between such closed condensers and the vapor space in the steam still, open condensers in each of said preceding stills opening into the vapor space thereof, connections from the vapor space of each preceding still, except the first, to the open condensers in the next preceding still of the series, and means for collecting together the condensate produced in each closed condenser with the condensate produced in the open condenser of the next succeeding still of the series.

26. In an apparatus of the class described, a series of stills, means for maintaining the stills of the series at successively higher vaporizing temperatures, means for feeding crude oil into the first still of the series and conveying oil from each of said stills to the next succeeding still of the series, a condensing coil in each still except the last, means for heating oil flowing between successive stills by means of condensate from succeeding stills of the series and means for conveying the vapor from each still to the condensing coil in a preceding still of the series.

27. In an apparatus of the class described, a series of stills, means for maintaining the stills of the series at successively higher vaporizing temperatures, means for feeding oil to the first still and from said first still to the second still and so on, a condenser in each still except the last, the condenser opening into the vapor space of the still, means for heating oil passing between successive stills by condensate of the vapors

given off in succeeding stills of the series, and means for leading vapors from the vapor space of each still, except the first, to the condenser in the next preceding still of the series.

28. In an apparatus of the class described, a series of stills, means for maintaining the stills at successively higher temperatures, means for feeding oil to the first still and from the first still to the second and so on, a condenser in each still comprising a main pipe and a series of branch pipes connected thereto, the branch pipes extending above the normal liquid level in the still and communicating with the vapor space therein, means for heating the oil flowing between successive stills by the condensates of the vapors given off in succeeding stills of the series, and means for conducting the vapors from the vapor space in each still, except the first, to the condenser in the next preceding still of the series.

29. In apparatus of the class described, a series of stills, means for maintaining the stills at successively higher vaporizing temperatures, means for supplying crude oil to the first still of the series and for conveying oil from said still to the next succeeding still of the series, and so on, a condenser in each still, except the last, and opening thereto, means for conducting vapors from each still into the condenser of the next preceding still of the series, a draw-off pipe for drawing off the condensate from each still condenser and heat interchangers for heating the oil passing between successive stills by this condensate.

30. In an apparatus of the class described, a series of stills, means for maintaining the stills at successively higher temperatures, a condenser in each still, except the last, connections from the vapor space of each still, except the first, to the condenser in the next preceding still of the series, and an intermediate condenser in each said connection, means for supplying to the same a mixture of condensates formed in the condensers in the next two preceding stills of the series, and a draw-off pipe connected to each still.

31. In an apparatus of the class described, a series of stills, means for maintaining the stills of the series at successively higher temperatures, means for feeding oil into the first still of the series and for conveying oil from each of said stills to the next succeeding still of the series, means for conveying vapors from each still, except the first, and discharging them into the next preceding still of the series, and means for condensing part of the vapors so conveyed comprising means for bringing them in heat exchanging relation with condensate thereof formed in said next preceding still.

32. In an apparatus of the class described,

a series of stills, means for maintaining the stills of the series at successively higher vaporizing temperatures, means for feeding crude oil into the first still of the series and 5 conveying oil from each of said stills to the next succeeding still of the series, means for conveying vapors from each still, except the first, and discharging them into the next preceding still of the series, and means arranged 10 intermediate the successive stills for condensing part of such vapors comprising means for introducing therein condensates formed from such vapors in said next preceding still mingled with the condensate of vapors given 15 off in the last-named still.

33. In an apparatus of the class described, a series of stills, means for maintaining the stills of the series at successively higher vaporizing temperatures, means for feeding 20 crude oil into the first still of the series and conveying oil from each of said stills to the next succeeding still of the series, means for introducing steam into a still near the 25 end of the series, closed condensers in the preceding stills and connections thereto from the vapor space of the steam still, open condensers in each of said preceding stills opening into the vapor space thereof and 30 connections from the vapor space of each preceding still, except the first, to the open condenser in the next preceding still of the series.

34. In an apparatus of the class described, a series of stills, means for maintaining the 35 stills at successively higher vaporizing temperatures, means for feeding crude oil into the first still of the series and conveying oil from each still to the next succeeding still of the series, means for introducing steam 40 into a plurality of stills near the end of the series, closed condensers in the preceding stills and connections thereto from the vapor spaces of the succeeding steam stills, open condensers in each of said preceding

stills opening into the vapor space thereof, 45 and connections from the vapor space of the stills other than the said plurality to the open condensers in the next preceding still of the series and means for collecting together the condensate produced in each 50 closed condenser with the condensate produced in the open condenser of the next succeeding still of the series.

35. In an apparatus of the class described, a series of stills, means for maintaining the 55 stills of the series at successively higher vaporizing temperatures, means for feeding crude oil into the first still of the series and conveying oil from each of said stills to the next succeeding still of the series, a condens- 60 ing coil in each still except the last, and means for conveying the vapor from each still to the condensing coil in a preceding still, including a cascade condenser and connections for conveying the vapor there- 65 through and pipes for leading condensate from the condensing coil in the next preceding still of the series to said cascade con- denser.

36. In an apparatus of the class described, 70 a series of stills, means for maintaining the stills of the series at successively higher vaporizing temperatures, means for feeding crude oil into the first still of the series and conveying oil from each of said stills to the 75 next succeeding still of the series, a condens- 75 ing coil in each still except the last, means for conveying the vapor from each still to the condensing coil in a preceding still, and means for separately leading away 80 the condensate from each condenser includ- 85 ing a series of heat exchangers, there being an exchanger for each preceding still in the series and means for leading oil passing between successive stills through the respective heat exchangers.

JOHN E. BELL.
